UNITED STATES PATENT OFFICE.

HARMON H. FULTON, OF INDIANAPOLIS, INDIANA.

FAN-FRAME FOR MILLSTONE-CURBS.

SPECIFICATION forming part of Letters Patent No. 242,294, dated May 31, 1881.

Application filed April 12, 1881. (No model.)

To all whom it may concern:

Be it known that I, HARMON H. FULTON, a citizen of the United States, residing at Indianapolis, in the county of Marion and State 5 of Indiana, have invented a new and useful Improvement in Skeleton-Frames for Supporting a Fan-Shaft, Fan, and Fan-Box, of which the following is a specification.

My invention relates to improvements in the 10 construction of a frame for supporting a fan, fan-shaft, and fan-box on the curbs of millstones, and the objects of my improvements are, first, to provide a light, strong, and durable frame for supporting the fan, fan-box, and 15 shaft; second, to provide the frame with stationary studs for securing the same to the curb of a millstone, and, third, to provide the frame with a step-box for supporting the lower end of the fan-shaft and holding oil for lubricating 20 it. These objects I accomplish by the device illustrated in the accompanying drawings, in which—

Figure 1 represents a vertical sectional view 25 of the entire device, and Fig. 2 is a plan view of the base-frame.

Similar letters in the two views refer to like parts.

A A A' A' represent the arms of the base-frame. The arms A A have at their outer 30 ends upward-projecting arms b b, to which the curved bar B is made fast by rivets or bolts d d. The upper central portion of the bar B is provided with a round hole and has the boss E secured to its upper side, as shown. 35 The central part of the spider or base-frame A A' is provided with a hole, w, immediately

under the hole in the bar B, in which the shaft D is inserted and operates.

To the lower side of the frame A A A' A' is secured by the bolts a a the pendent step-box 40 C, with a recess, n, in the center of the cup m for the lower end of the shaft D to operate in. The cup m is for the purpose of holding oil to lubricate the lower end of the shaft. The intervening space between the top of the oil-cup 45 m and bottom of the frame A is for the pulley F, which is keyed or made fast to the fan-shaft D, and is driven by a belt from a pulley attached to the running-stone of the mill. (Not shown.) The arms A A A' A' of the frame 50 have studs c c projecting downward for securing the frame to the curb of a mill.

What I claim as new, and desire to secure by Letters Patent, is—

A fan-frame for the curb of a millstone, consisting of the base-frame A A A' A', the arms A A having upwardly-projecting ends b b, and each arm provided with a downwardly-projecting stud c, combined with the pendent step-box C below, having oil-cup m and recess 60 n for the shaft D, the metal bar B above, secured to the arms b b and provided with a hole in its top, and the boss E and the fan-shaft D, all constructed and combined substantially as shown and described. 65

In testimony whereof I have signed my name to this specification in the presence of two subscribing witnesses.

HARMON H. FULTON.
